UNITED STATES PATENT OFFICE.

HENRY C. ADAMS, OF FLAGSPRINGS, MISSOURI.

SHINGLE GAGE AND HOLDER.

SPECIFICATION forming part of Letters Patent No. 780,697, dated January 24, 1905.

Application filed May 7, 1904. Serial No. 206,910.

To all whom it may concern:

Be it known that I, HENRY C. ADAMS, a citizen of the United States, residing at Flag-springs, in the county of Andrew and State of 5 Missouri, have invented certain new and useful Improvements in Shingle Gages and Holders, of which the following is a specification.

This invention relates to an improved form 10 in the construction of buildings, particularly for the purpose of supporting shingles in proper alinement preparatory to nailing same permanently in position.

The invention comprises, essentially, the 15 supporting-bar, upon which the shingles rest and which obviates the necessity of chalking a line to indicate the relative positions of said shingles, and clamp devices by which the supporting-bar is held in position, which devices 20 admit of adjustment and removal of the supporting-bar whenever necessary.

For a full description of the invention and the merits thereof and also to acquire a knowledge of the details of construction of the means 25 for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view showing the application of the invention in practical use. 35 Fig. 2 is a rear view of the supporting-bar, partially broken away, and one of the clamp devices carried thereby. Fig. 3 is a vertical sectional view bringing out more clearly the construction of the clamp device.

Corresponding and like parts are referred to in the following description and indicated in all the views of the drawings by the same reference characters.

The invention is shown applied in its use 45 in connection with shingles. However, it will be understood that the same is adapted to support siding or the like preparatory to securing same permanently in position.

The device consists of the shingle-support- 50 ing bar 1, which may be of a suitable length

to support any number of shingles when the latter are disposed thereon preparatory to being nailed to the building. The supporting-bar is provided with peculiar clamp devices by which the same is adapted to be secured to the building which is being shingled, and since 55 these clamp devices are of the same form one only will be described. Each clamp device is composed of a supporting member 2, transversely widened at its upper end, as shown at 60 3, being secured at this portion to the supporting-bar 1 by suitable fastenings 4. The supporting member 2 is provided adjacent its upper end with engaging means in the form of projections 5. Pivoted to the supporting 65 member 2 is a clamp member 6, and this latter member co-operates with the supporting member to properly support the bar 1. The upper ends of the members 2 and 6 of the clamp device are adapted to receive therebetween a shingle or board which has already 70 been secured in position and by a clamping action against said board or shingle to rigidly hold the supporting-bar 1 in such a position as to admit of disposal upon this bar 1 of the 75 shingles which are to be secured in place. The clamp members would of course be engaged with a lowermost row of shingles preparatory to disposal thereon of the loose shingles which are to be nailed in position in 80 proper alinement. In order to cause a clamping action of the members 2 and 6 against the secured shingles, the member 2 of each of the clamp devices is provided at its lower end with a cam-lever 7, and the latter is adapted 85 to co-operate with the adjacent clamp member to effect the necessary clamping action above mentioned. Springs 8 are disposed between the upper ends of the members 2 and 6 and normally tend to hold such ends apart. The 90 co-operation of the cam-lever 7 is to effect a clamping action of the upper ends of the members 2 and 6 against the tension of the springs 8, and a pivotal movement of the cam-lever 7 will accomplish this result. The springs 8 95 are preferably mounted upon pintle members 9, which constitute pivotal connections between the supporting members 2 and clamp members 6 of the clamp devices, which are carried by the supporting-bar.

In the use of my invention as soon after a row of shingles has been nailed in position the clamp-levers 7 are actuated, so as to disengage the clamp devices of the supporting-bar, and this bar is elevated, so as to support the next higher row of shingles preparatory to nailing same in position. The point of engagement of the clamp devices of the supporting-bar may be varied, and in engaging these devices it is but necessary to insert the upper end of the clamp members 6 thereof beneath an adjacent shingle, and operation of the cam-levers 7 will cause the projections 5 of the supporting members 2 to positively engage against the outer sides of the shingles. The holder is moved progressively as each row of shingles is nailed securely in position. A projection or projections 10 may be extended from the inner face of the clamp members, so as to limit the upward movement of these members relative to the shingles, which are to be engaged in positioning the supporting-bar 1, the said projections 10 being clearly shown in Fig. 3.

Having thus described the invention, what is claimed as new is—

1. In a device of the class described, the combination of a supporting-bar, clamp devices carried by said bar, each of said clamp devices comprising a supporting member secured to the supporting-bar, a clamp member pivoted to the supporting member and coöperating at one end with an end of said supporting member, and a cam-lever carried by the opposite end of the supporting member to effect clamping action of the same and the clamp member.
2. In a device of the class described, the combination of a supporting-bar, clamp devices, each clamp device comprising a supporting member secured at its upper end to the supporting-bar, engaging projections extended from the upper end of the supporting member, a clamp member, means pivotally connecting the clamp member between its ends to the supporting member, the upper end of said clamp member coöperating with the supporting member to position the supporting-bar, spring means normally holding the upper ends of the supporting and clamping members apart, a cam-lever carried by the lower end of the supporting member and adapted to engage the lower end of the clamp member to effect clamping action of these members, and a projection extended from the clamp member between its upper end and the point of pivotal support thereof.

In testimony whereof I affix my signature in presence of two witnesses.

HENRY C. ADAMS. [L. S.]
